UNITED STATES PATENT OFFICE.

JAMES J. HARTLEY, OF SYRACUSE, NEW YORK, ASSIGNOR TO GENERAL ELECTRIC COMPANY, A CORPORATION OF NEW YORK.

INCANDESCENT-LAMP SOCKET.

No. 805,287.

Specification of Letters Patent.

Patented Nov. 21, 1905.

Application filed May 1, 1903. Serial No. 155,132.

To all whom it may concern:

Be it known that I, JAMES J. HARTLEY, of Syracuse, in the county of Onondaga, in the State of New York, have invented new and 5 useful Improvements in Incandescent-Lamp Sockets, of which the following, taken in connection with the accompanying drawings, is a full, clear, and exact description.

This invention relates to improvements in 10 incandescent-lamp sockets in which a suitable electric switch is mounted upon and within a base of insulating material and is electrically connected in the electric-lighting circuit for making and breaking the circuit through the 15 lamp.

The broad object of the various improvements hereinafter set forth is to simplify the structure and to economize in the cost of labor and material in the manufacture of the 20 sockets.

The specific objects are, first, to mount the switch and its supporting - frame within a sectional insulator-base in such manner that any variation due to shrinkage or other 25 imperfections in the manufacture of the insulator-sections, such as porcelain, does not interfere with the easy and rapid assemblage of the parts nor with the perfect contact of the switch members for making and breaking 30 the circuit; second, to insulate the line - terminals of opposite polarity from each other to reduce the liability of short-circuits or leakage of the current; third, to adapt the socket for use in connection with either the center 35 screw - stud or screw - shell rim contact—in other words, to permit the socket to be readily interchanged for use in connection with the

Thomson & Houston or Edison lamps; fourth, to hold the insulating-cap in the head of the 40 outer shell in position by means of lugs or ears stamped or pressed inwardly and upwardly from the body of the cap of the shell, thereby utilizing the stock which is cut out to form a bayonet-lock as the fastening means for the 45 insulating - cap; fifth, to utilize portions of the shell for forming a nut or nuts to receive the fastening - screws which secure the cap to the main outer shell; sixth, to mount the terminals and contact members wholly upon 50 one of the insulator-base sections, so that they may all be removed at the same time and inspected or repaired without displacing the same.

Further objects will appear in the subsequent description.

55

In the manufacture of porcelain bases, particularly where they are formed in sections, it has been found that the shrinkage and other imperfections necessitates careful adjustment of the switch mechanism when assembling 60 the same in the socket or base in order that the contact may be perfect, and it frequently happens that this adjustment is neglected, and therefore the making and breaking of the circuit is unreliable. This is particularly true 65 when the **U**-shaped frame which is generally employed is arranged in an upright position—that is, with the arms extending in the direction of the axis of the socket—in which instance it is customary to make contact with 70 the periphery of the threaded shell, which is secured to the insulator-base to receive the threaded rim of the lamp. It will also be observed that in this class of lamps and sockets the member which contacts with the center 75 terminal of the lamp is imperfectly insulated from the switch mechanism, which insulation is generally nothing more than an air-space and sometimes the interposition of mica or similar insulating material. It will readily be seen that 80 when nothing but an air-space is left between this contact member and the switch mechanism there is more or less liability of the arcing of the current between the parts and that when the mica or other insulating material is 85 interposed it adds materially to the cost of the socket. My invention is designed to overcome these defects and, further, to add to the general safety and efficiency of the socket and its operating parts.

90

In the drawings, Figure 1 is a longitudinal vertical sectional view of a socket embodying the various features of my invention, a portion of a lamp being shown as operatively mounted in the socket. Figs. 2, 3, and 4 are 95 sectional views taken, respectively, on lines 2 2, Fig. 1, 3 3, Fig. 2, and 4 4, Fig. 3, the lamp being omitted in Fig. 2, and the outer shell is omitted in Fig. 4. Fig. 5 is an elevation, partly in section, of the detached insulator-base and threaded metallic socket, showing particularly one of the screws which unite the metal socket and base-sections together. Fig. 6 is an inverted view of the main insulator-section of the base, showing particularly 100 the manner of mounting the **U**-shaped frame

105

and switch mechanism. Fig. 7 is a sectional view taken on line 7-7, Fig. 5, showing the base-sections as separated from each other for the purpose of more clearly illustrating the 5 terminals and switch mechanism. Figs. 8 and 9 are detail views of the detached insulator-base sections, the line-terminals being shown in Fig. 9. Figs. 10 and 11 are perspective views of the detached key-frame and one of 10 the spring-terminals, which is adapted to be secured to said frame. Figs. 12 and 13 are detail views of the detached key-spindle and the metal threaded socket for receiving the lamp. Fig. 14 is a sectional view similar to 15 Fig. 1, omitting the outer shell and the upper base-section, and showing the lower base-section as equipped with a center threaded stud for receiving a Thomson-Houston lamp having a threaded center socket. Fig. 15 is 20 a vertical sectional view similar to Fig. 4, except looking in the opposite direction and showing the threaded center stud and socket seen in Fig. 12. Fig. 16 is an inverted plan view of the lower insulator-base section seen 25 in Figs. 12 and 13, showing the center and rim contact members for the lamp-terminals. Figs. 17 and 18 are respectively inverted plan 30 and side elevation of the detached cap of the outer shell, showing the means for fastening the inner insulating-cap in position. Fig. 19 is a sectional view taken on line 19-19, Fig. 17. Fig. 20 is a vertical sectional view 35 through the outer shell and its inner lining of insulating material. Fig. 21 is an elevation of the upper end of the shell seen in Fig. 20. Fig. 22 is a sectional view taken on line 22-22, Fig. 20, showing the means for reinforcing the threaded tap in the shell. Fig. 23 is a perspective view of a fragmentary portion 40 of the shell, showing a modified means for reinforcing the tap. Fig. 24 is a sectional view taken on line 24-24, Fig. 23. Fig. 25 is a perspective view of the detached nut seen 45 in Figs. 23 and 24.

Similar reference characters indicate corresponding parts in all the views.

In carrying out the several objects stated I provide a metal shell consisting of a main section 1 and a cap 2, the cap end of the shell 50 being provided with threaded openings 3 through its side walls for receiving clamping-screws 4, portions of the shell at the opposite sides of said threaded opening being cut or stamped from the body of the shell to form 55 wings 5, which are folded inwardly across the opening 3, said inwardly-folded portions being also tapped and threaded for receiving the inner end of the screw 4 and reinforcing the mat 1 at this point to form a nut, as seen in 60 Figs. 3, 20, 21, and 22.

The end of the cap 2 is adapted to telescope with the adjacent end of the main shell 1 and preferably incloses the upper end of said shell, said cap being provided with a recess 65 6, extending inwardly and laterally from its

end edges to receive the screws 4, and together with said screws forms what may be termed a "bayonet-lock" for holding the cap in operative position. In forming these recesses 6 it is customary to cut away the stock; 70 but it has been found that portions of this stock which has been heretofore wasted may be utilized to hold an insulating-cap, as 75 7, in operative position within the cap 2, and therefore the portions 6' of the metal which forms the upright of the recess 6 is left attached at its upper end and is then bent inwardly and upwardly against the inner faces of the insulating-cap 7, as seen in Figs. 1, 2, 17, and 19, and it is thus apparent that the 80 only metal which is actually wasted is that which forms the lateral portion of the recess 6.

Although I have described the threaded opening 3 as reinforced by folding parts of 85 the stock of the shell inwardly to overlap each other, as seen in Fig. 22, it is desirable in some instances to use a separate nut 5', as seen in Figs. 23 and 25, in which instance I also stamp or cut out portions of the metal of 90 the shell and bend the same inwardly to form tongues 8, which enter grooves 9 in the adjacent ends of the nut 5', and thus hold the nut in operative position with its threaded aperture alined with the aperture 3. 95

The outer shell 1 is provided with an inner lining or shell 2' of insulating material which serves to prevent short-circuiting of the power-current to said shell.

Mounted within and inclosed by the shell 100 1 and cap 2 is an insulator-base comprising upper and lower sections 10 and 11, the upper section being regarded as the main body, and is provided with a central recess 12 and opposite cut-outs 13, the recess 12 serving to 105 receive the switch mechanism presently described, and the cut-outs 13 receive the binding-posts to which the line-wires are secured, and it is thus apparent that the terminals of the switch are insulated from the binding-posts by the walls of the recess 12, and that the opposite terminals of different polarity of the line-wires are also separated from each other by the same inclosing walls of the recess 12. This recess extends inwardly from 110 the lower end of the section 10, but only part way through said section, so as to leave an imperforated insulating-wall at the upper end of the recess, which adds materially to the safety and efficiency of the socket in preventing 115 short-circuits and leakage of the current. 120

The lower base-section is of substantially the same diameter as the upper section and extends across the open end of the recess 12, thereby forming a cap of insulating material 125 for the open end of the recess, which cap also forms the lower end walls of the cut-outs 13. This cap or insulating section 11 is provided with a flange or raised portion 14, which fits within the recess 12, and not only serves to 130

hold the sections from lateral displacement with reference to each other, but also forms a seat upon which the switch-frame rests, the upper wall of the recess being formed with a 5 similar seat 15 for engaging the upper edge of said switch-supporting frame, so that the frame is impinged between the seats 14 and 15 when the base-sections are secured together. This switch-supporting frame preferably consists of a U-shaped bar 16, which is arranged flatwise in the recess 12, with its arms 17 projecting laterally in a direction at substantially right angles to the axis of the socket, said frame being provided with a laterally-projecting lug 18, having a threaded aperture to receive a screw 19, which latter is passed through an aperture in the insulator-section 11 and serves to secure the frame to said section.

When my improved socket is to be used with 10 an Edison lamp, I provide the same with a screw-shell 20, which is secured to the base-section 11 by the screw 19 or by additional screws or clamping-bolts 21, the latter clamping-bolts being passed through apertures in 15 the insulating-sections at one side of the recess 12, and their upper ends are threaded and engaged by suitable nuts 22, embedded in recesses in the upper face of the upper section 10. When this form of threaded socket 20 is 20 employed, it is cut away at 23 to receive a contact member 24, which consists of a spring-arm having one end secured to the base-section 11 by a screw 25, and its other end extends downwardly beneath the lower face of 25 the section 11 and contacts with the center terminal 26 of the lamp 27, the same screw which holds the contact member 24 in place being passed through an aperture in the base-section 11 and engages one of the binding 30 posts or terminals 28 of the line-circuit wire 28', the other wire of the line-circuit being connected to a similar binding post or terminal 29, mounted upon the base 11 and secured thereto by a screw 30. Secured to the intermediate portion of the frame 16 is a U-shaped 35 spring-terminal 31, which is also arranged edgewise longitudinally of the socket and normally bears against a revolving cam 32. This cam is mounted upon a spindle 33, Fig. 12, 40 which is passed through elongated apertures 34 in the arms 17 of the frame 16, said spindle being provided with fins 35, one of which is engaged to lock the cam 32 to rotate with the shaft or spindle, and the other is arranged 45 in close proximity to one of the arms 17 to prevent endwise displacement or withdrawal of the spindle. It may be stated here that the arm adjacent to the latter fin of the spindle 33 is of sufficient length to permit the insertion of the fin therethrough when the parts 50 are first assembled; but after the spindle is operatively mounted in the frame the opposite walls of the slot at one end are compressed so as to prevent the withdrawal of the key-spindle.

55 A second spring-terminal 36 is secured to the base-section 11 by the screw 30, so that the adjacent ends of the binding-post 29 and terminal 36 are lapped one upon the other and are therefore in electrical connection with each other, the terminal 36 rising from the 60 base-section 11 in alinement with the cam 32, so that when the cam is rotated it is moved into and out of contact with the terminal 36, and thereby makes and breaks the circuit through the terminals 31 and 36. It will thus 65 be seen that one of the line-wires is electrically connected to one of the lamp-terminals, as 26, through the medium of the binding-post 28, screw 25, and contact member 24, and that the other line-wire is electrically connected to 70 the binding-post 29 and spring-terminal 36, the spring-terminal 31 being electrically connected to the other lamp-terminal, as the screw-threaded rim 37, through the medium of the 75 threaded metal socket 23, screw 19, and frame 80 16, to which latter the spring-terminal 31 is secured. It is now evident that when the cam 32 is in contact with the terminal 36 the binding-post 29 is electrically connected to the lamp-terminal 37 and that when said cam is 85 not in contact with the terminal 36 the circuit is broken.

It will be noted that the terminal 36 stands in an upright position substantially parallel with the axis of the socket, so that any variation in the length of the socket or adjustment of the frame 16 makes no difference with the contact, which is always the same. It will also be observed that all of the binding-posts, switch members, and contact-terminals 90 of the socket are mounted upon the base-section 11 and may be removed with said base-section by simply removing the screws 21, which secure the base-sections together, this being accomplished without displacing any of 95 the terminals or switch members, except, of course, those which are attached to the lamp.

In Figs. 14, 15, and 16 I have shown my improved socket as used in connection with what is known as the "Thomson & Houston" lamp, 100 having a central metallic threaded bushing 40 and a metal rim contact 41, the lower section 11 of the insulator-base being provided with a threaded stud 42 and spring-terminal 43, the threaded stud 42 taking the place of the spring 105 contact member 24 (seen in Figs. 1, 2, and 7) and engages the threaded bushing 40 and forms one of the lamp-terminals for electrically connecting the same to the binding-post 28, while the rim-contact member 41 is connected to the 110 other lamp-terminal and contacts with the terminal 43, which is in electrical connection with the key-frame 16 through the medium of the screw 19. The threaded stud 42 is fastened to the insulator-base section 11 by a screw 44, 115 and it now becomes evident that in order to adapt the socket for use in connection with the Thomson & Houston lamps, it is simply necessary to remove the spring contact member 24 and threaded socket 20 and to substi- 120

125 130

tute the screw-threaded stud 42 in place of the spring 24, while the contact member 43 is substituted for the threaded socket 20, the same screw 25 which electrically connects the spring 24 to the binding-post 28 serving to electrically connect the screw-threaded stud 42 to said binding-post, and the same screw 19 which electrically connects the threaded socket 20 to the frame 16 also serves to electrically connect the contact member 43 to said frame. It is thus seen that the socket is readily interchangeable from one form of lamp to the other without in any way changing the construction of the switch mechanism or line-terminals, and in fact every part of the socket remains the same in both instances, except for the substitution of the parts 42 and 43 for the members 24 and 20.

Having thus described my invention, what I claim, and desire to secure by Letters Patent, is—

1. In an incandescent-lamp socket, a base of insulating material having a recess, in combination with a switch in the recess and including a pair of terminals and a rotary cam for connecting the terminals, one of the terminals consisting of a spring-arm extending in a direction at substantially right angles to the axis of the socket and having its free end movable laterally with reference to said axis.

2. In an incandescent-lamp socket, a base of insulating material having a recess, in combination with a switch in the recess and including a pair of terminals and a rotary cam for connecting the terminals, one of the terminals consisting of a flat spring disposed flatwise with reference to the axis of the socket and secured at one end, the free end extending in a direction at substantially right angles to the said axis and springing laterally.

3. In an incandescent-lamp socket, a base of insulating material having a recess in combination with a U-shape frame seated in the recess with its arms projecting in a direction at substantially right angles to the axis of the socket, a spring-terminal secured at one end to the frame and springing laterally with reference to said axis, a second terminal, and means for electrically connecting and disconnecting said terminals.

4. In an incandescent-lamp socket, a base comprising two separable insulator-sections secured together end to end and each having a seat, a U-shape frame disposed within the base at right angles to the axis and having its opposite edges engaged by said seats whereby the frame is held in position, and an electric switch within the base and having its movable member journaled in said frame.

5. In an incandescent-lamp socket, a base of insulating material comprising two sections secured together end to end, and each provided with a seat and a recess, a U-shape frame resting on said seats at right angles to the axis of the base, a rotary spindle jour-

naled in the frame, a cam on the spindle revolving in the recesses, and terminals adapted to be contacted by said cam.

6. In an incandescent-lamp socket, the combination with a switch including terminals and a rotary cam, a U-shape frame the arms of which are provided with elongated slots closed at both ends, a rotary spindle inserted in the slots and receiving the cam, said spindle having laterally-projecting fins, one of the slots having its opposite walls compressed at one end to prevent the withdrawal of the spindle.

7. In an incandescent-lamp socket, a base of insulating material comprising two sections secured together end to end, one section having a recess opening from one end, a U-shape frame loosely mounted in the recess and held in position by the other section, a rotary spindle journaled on the frame, a cam on the spindle, a terminal secured to one of the sections, a second terminal secured to the frame, said terminals being adapted to be electrically connected and disconnected by the cam.

8. In an incandescent-lamp socket, an insulator-base composed of two sections secured together end to end, one section having a central recess opening from one end, a metallic frame disposed in the recess at right angles to the axis of the base, a spring-terminal secured to the frame, a second spring-terminal secured to one of the insulator-sections, a rotary spindle journaled in the frame, and a contact member on the spindle having a wiping or brush contact with said terminals and forming an electrical connection between said terminals.

9. In an incandescent-lamp socket, an insulator-base composed of two sections, one of the sections having a recess opening from one of its end faces, an electric switch having a rotary key, a U-shape frame lying wholly within the recess with its arms projecting in a direction at substantially right angles to the axis of the socket and supporting the rotary key and means for clamping the sections together.

10. In an incandescent-lamp socket, an insulator-base composed of two sections, one of the sections having a center recess and two side cut-outs opening from one of its end faces, an electric switch in the recess and including a pair of terminals and a rotary contact member, and binding-posts in the side cut-outs.

11. In an incandescent-lamp socket, an insulator-base composed of sections secured together end to end, one of the sections having a recess opening from the end adjacent to the other section, a U-shape frame in the recess having its arms extending laterally with reference to the axis of the socket, a spring-terminal electrically connected to the frame, a second spring-terminal, a rotary contact member for electrically connecting said terminals in combination with a lamp having a terminal electrically connected to the frame.

12. In an incandescent-lamp socket, an outer shell having a metal cap telescoping therewith, an insulator-cap within the metal cap, the latter having tongues stamped or pressed inwardly for holding the insulator-cap in position.

13. In an incandescent-lamp socket, an outer metal shell having a removable cap telescoping therewith, said shell being provided with an aperture and having a portion thereof at one side of the aperture cut or stamped to form a tongue, the latter being folded across the opening and provided with a threaded aperture alined with the former aperture, in combination with a screw entering said apertures for securing the cap to the main shell.

14. In an incandescent-lamp socket, a base of insulating material composed of sections secured together end to end, one section having a central recess and two side cut-outs ²⁰ independent of said recess, an electric switch mounted upon the other of the said sections, binding-posts for the line-wires secured to the latter section and a pair of contact members also secured to the latter section to contact with the lamp-terminals. ²⁵

In witness whereof I have hereunto set my hand this 27th day of April, 1903.

JAMES J. HARTLEY.
